CLAIM

The ornamental design for a test strip, as shown and described.

DESCRIPTION

FIG. 1 is a top perspective view of a first embodiment of a test strip;

FIG. 2 is a top view thereof;

FIG. 3 is a bottom perspective view thereof;

FIG. 4 is a bottom view thereof;

FIG. 5 is a left side view thereof;

FIG. 6 is a right side view thereof;

FIG. 7 is a front view thereof, on a larger scale;

FIG. 8 is a rear view thereof, on a larger scale;

FIG. 9 is a top perspective view of a second embodiment of a test strip;

FIG. 10 is a top view thereof;

FIG. 11 is a bottom perspective view thereof;

FIG. 12 is a bottom view thereof;

FIG. 13 is a left side view thereof;

FIG. 14 is a right side view thereof;

FIG. 15 is a front view thereof, on a larger scale; and,

FIG. 16 is a rear view thereof, on a larger scale.

The broken lines in FIGS. 1-16 are included for the purposes of illustrating environmental elements only and form no part of the claimed design.
